UNITED STATES PATENT OFFICE.

FRANK L. KASPAR, OF CHICAGO, ILLINOIS.

DESIGN FOR A MOUTHPIECE FOR REED MUSICAL INSTRUMENTS.

54,420.

Specification for Design.

Patented Feb. 10, 1920.

Application filed September 12, 1919. Serial No. 323,404. Term of patent 14 years.

To all whom it may concern:

Be it known that I, FRANK L. KASPAR, a citizen of the United States, residing at Chicago, in the county of Cook and State of Illinois, have invented a new, original, and ornamental Design for a Mouthpiece for Reed Musical Instruments, of which the following is a specification, reference being had to the accompanying drawing, forming part thereof.

Figure 1 is a side elevation showing my new ornamental design for mouth piece for reed musical instruments.

Fig. 2 illustrates the front elevation of same.

Fig. 3 illustrates the back view.

Fig. 4 is the bottom view of Fig. 1.
I claim:

The ornamental design for a mouthpiece for reed musical instruments as shown.

In witness whereof I have hereunto subscribed my name this 8th day of September, 1919.

FRANK L. KASPAR.
